[57] ABSTRACT

A footboard assembly for use with a bed to provide support and positioning of the feet of a bedridden person including a pair of brackets adapted for mounting on opposite side rails of a bed frame, near the foot of the bed. Extending upwardly from the brackets are a pair of tubular vertical support arms, with a foot-supporting panel extending therebetween over the bed. Each bracket includes a C-channel member which receives the bed frame within its cavity. A bolt received through one of a plurality of holes in the web of the C-channel member clamps the bed rail between a portion of the bolt head and the web, with the shank of the bolt disposed adjacent the lower edge of the bed rail. The bolt head is cut chordally to fit flush with the inner surface of the flange of the C-channel member. The plurality of holes permits the assembly to be clamped to beds of varying rail configuration.

HOSPITAL BED FOOTBOARD ASSEMBLY

BACKGROUND OF THE INVENTION

For a person who must be confined to a bed for an extended period of time, a footboard assembly is often employed to provide necessary positioning and support of the legs of the bedridden person. The feet of a person lying in bed on her back will normally extend obliquely from the legs, as opposed to extending generally perpendicularly from the legs when she is standing. It has been found that when the foot remains relaxed in the obliquely extending position for long periods of time, as is the case for a bedridden patient, the muscles of both the legs and feet undergo a deleterious deterioration. To prevent this occurrence, devices have been designed for use with hospital beds which maintain the feet and legs in positions which allow the muscles to be suitably conditioned to make up for their lack of proper exercise.

In the prior art, these devices have taken the form of footrests supported on a bed and selectively movable between beds. These footrests have had in common the failure to accommodate hospital beds of differing configurations, constructions, and dimensions. The differences, such as the width of the frame and springs, the nature of the frame rails, the configuration of the safety rails, and the like, have accounted for the fact that many prior art footrests cannot be secured to various hospital beds with the rigidity required to provide stimulation to the legs and feet of the bedridden person. For example, some footrests are provided with clamping brackets which accommodate a variety of bed frame members, yet do not clamp effectively to any of them.

SUMMARY OF THE INVENTION

The present invention provides a footboard assembly which is quickly and securely fastened to beds of differing widths, and furthermore includes a novel bracket which accommodates and fastens the footboard assembly to various bed side rails commonly in use. The invention generally comprises a footboard extending across the foot of a bed and adjustably supported at the ends by bolts received in a pair of footboard brackets. The footboard brackets include tubular portions in which a pair of vertical supports are received and secured by bolts received in one of a plurality of vertically spaced holes in the vertical supports. The vertical supports are secured to a pair of bed rail brackets. Each rail bracket includes a lateral C-channel member which receives a portion of the bed rail between its flanges with the upper flange resting on the bedrail. A bolt passing through one of a plurality of holes in the web of the C-channel member clamps a portion of the bed rail between the channel web and the bolt head. The bolt is secured with a quickly removable wing nut, and the bolt head is trimmed chordally to fit flush with the lower flange of the C-channel member. The plurality of holes in the web permits the bolt to clamp to bed rails of various sizes and configurations.

THE DRAWING

FIG. 1 is a perspective view of the present invention installed on a bed.

FIG. 2 is a front elevation of a portion of the assembly shown in FIG. 1, showing the mounting means for securing the footboard to the vertical support.

FIG. 3 is a front elevation of a portion of the invention shown in FIG. 1, detailing the bed rail bracket.

FIG. 4 is a side elevation of a portion of a further embodiment of the bed rail bracket.

FIG. 5 is a cross-sectional elevation taken along line 5-5 of FIG. 4.

FIG. 6 is a side elevation of a portion of the bed rail bracket depicted in FIG. 3.

FIG. 7 is a cross-sectional elevation taken along line 10 7-7 of FIG. 6.

DESCRIPTION OF THE PREFERRED EMBODIMENT

As depicted in the drawing, there is shown in FIG. 1 15 a footboard assembly 8 mounted on spaced, longitudinal bed rail members 9 and 10 of a bed frame 11. Although the footboard assembly will be described with reference to mounting on bed rails which comprise a channel member having a laterally extending portion 20 and a vertically extending portion, it should be noted that the present invention is not limited in application to this type of bed side rail.

The footboard assembly 8 includes a footboard 12 25 extending laterally across the end of the bed frame 11 for supporting the feet and legs of a person in repose on the bed. As described in the foregoing, the footboard positions the feet to maintain desirable muscle tone in the feet and legs of a bedridden person. At either end the footboard is adjustably secured to a footboard bracket 13. As shown in FIG. 2, each bracket 13 30 comprises a plate 14 joined at one edge to a tubular member 16. The plate 14 includes lateral slots 17 for receiving bolts 18 therethrough, the bolts extending through holes in the footboard and secured with wing nuts 19.

The tubular member 16 includes a plurality of vertically spaced lateral holes 21 therethrough. Received within the tubular member 16 is a vertical support 22, 40 which comprises a vertically extending tube with a single lateral hole 23 through the upper extremity thereof. A bolt 24 extending through one of the holes 21 and hole 23 and secured with a wing nut 26 supports the end of the footboard. It may be appreciated that the appropriate hole 21 may be chosen so that the footboard is disposed at the optimum height above the bed frame and mattress. In this manner the assembly may be adjusted to the differing height configurations of various beds and to the comfort of the bedridden person. Furthermore, the slots 17 in conjunction with the bolts 18 45 permit the assembly to be adjusted in width to accommodate various bed width configurations.

A pair of vertical supports 22 are provided to engage brackets 13 and support both ends of the footboard. A pair of bed rail brackets 31 which clamp to the bed rails 55 9 and 10 are provided to rigidly retain the vertical supports 22. As shown in FIG. 3, each bed rail bracket comprises a vertically aligned tubular member 32 which is welded or otherwise joined to a laterally disposed C-channel member 33. The tubular member 32 60 which receives the vertical support 22 includes an inwardly directed radial shoulder 34 at the lower end which establishes a seat for the lower end of the vertical support 22.

The C-channel member 33 comprises upper and lower lateral flanges 36 and 37 joined by a vertical web 38 therebetween. When the footboard assembly is 65 installed on a bed, the brackets 31 are disposed so that

the upper flange 36 bears on the lateral surface 39 of the bed rail. A plurality of holes 41 extending through the web 38 are provided, with bolts 42 extending through selected holes 41.

It should be noted that commonly used bed frames are frequently fabricated of "angle iron" channel stock, which comprises the lateral portion 39 joined to a vertically extending portion 44. However, the width of the portion 39 and the vertical dimension of the portion 44 varies from bed to bed, according to the particular channel stock used by the manufacturer of the bed. This may be readily apparent by referring to the channel stock depicted in FIGS. 4 and 5, as compared with the channel stock shown in FIGS. 6 and 7.

To accommodate the various channel stock which comprises the bed side rails, the holes 41 are positioned in the web so that each pair of holes is disposed adjacent to the lower edge 46 of one of the commonly used channel members when the upper flange 36 is resting on the lateral portion 36 of the channel. The bed rail bracket is thereby easily clamped to the bed side rail by passing a pair of bolts 42 through the appropriate pair of holes so that the bolt shanks are adjacent lower edge 46. A wing nut 50 tightened onto each bolt causes the rail portion 44 to be clamped tightly between the bolt head 48 and the web 38.

The bolt head 48, which is of large diameter and rounded, is modified to further facilitate easy installation and removal of the footboard assembly. The head 48 is trimmed along chordal line 49, so that the chordal side is adjacent and abuts the lower flange 37 when the bolt is disposed in the lowest hole. The bolt is prevented by the flange from rotating as the wing nut is tightened thereon. To provide the same effect when the bolt is disposed in other of the holes 41, the bolt head 35 may be trimmed along another chordal line 51 as shown in FIGS. 6 and 7, and as many more chordal lines as are appropriate for the plurality of holes 41.

Thus it may be appreciated that the brackets 31 clamp effectively to the side rails of a bed, and that they accommodate a variety of side rail configurations. Fur-

ther, the brackets can be easily loosened and slid along the side rails to position the footboard assembly in the optimum position for therapeutic treatment of the feet and legs of the bedridden person. And, the present invention as described in the foregoing is easily adjustable both in width and in height above the bed frame.

I claim:

1. A foot support assembly for beds, comprising a pair of support brackets for mounting on opposite side rails of a bed frame, each support bracket including a channel member with an upper flange and a lower flange extending equally from a medial web and defining therebetween a cavity for receiving a side rail of the bed, a plurality of holes disposed in said web, at least one bolt received through one of said plurality of holes in said web and secured thereto for clamping the bed side rail between a portion of the head of said bolt and said web; each of said support brackets including a vertically disposed tubular member secured to said web; a pair of support arms each received in said tubular member and supported thereby, and a foot support member extending between said support arms and secured thereto.

2. The foot support assembly of claim 1, wherein said head of said bolt comprises a generally circular member including a chordal surface for abutting one of said flanges of said support bracket in non-rotating fashion.

3. The foot support assembly of claim 2, wherein said plurality of holes are varyingly spaced from said lower flange to accommodate differing bed side rails, and said bolt head includes a plurality of chordal surfaces, each adapted to abut one of said flanges with said bolt disposed in a selected one of said plurality of holes.

4. The foot support assembly of claim 2, wherein each of said support arms includes a plurality of vertically spaced apertures through the upper extremity thereof, and said foot support member includes bolt means at each end thereof for engaging one of said apertures.
